J. W. GILES

YARN LET-OFF CONNECTION

Filed April 10, 1922

FIG. 1.

FIG. 2.

Inventor
J. W. Giles,

By *Alfred Murphy Jr.*
Attorney

UNITED STATES PATENT OFFICE.

JOHN W. GILES, OF GREER, SOUTH CAROLINA.

YARN LET-OFF CONNECTION.

Application filed April 10, 1922. Serial No. 551,220.

To all whom it may concern:

Be it known that I, JOHN W. GILES, a citizen of the United States, residing at Greer, in the county of Greenville and State 5 of South Carolina, have invented certain new and useful Improvements in Yarn Let-Off Connections; and I do hereby declare the following to be a full, clear, and exact description of the invention, such as will enable others skilled in the art to which it 10 pertains to make and use the same.

This invention relates to an apparatus for the yarn let-off mechanism of a loom.

The main object is to provide a novel connection between the let-off rod and an operating rock shaft therefor which will avoid the use of a cotter pin or key usually employed to overcome liability of frequent breakage of the connection and consequent 20 falling off or displacement of the drive rod, causing the warp to tighten and throw out the shuttle and break ends in considerable numbers.

Another object is to provide a construction in which one of the connected parts has a substantially T-shaped head and the other part has an enlarged slot to coact therewith and of a shape to enable reinforcement of the parts where the greatest 30 wear and strain occurs thereon.

With the above and additional objects such as will hereinafter appear, in view, the invention has been embodied in one preferred form as illustrated in accompanying 35 drawings:

In said drawings:—

Figure 1 is an elevation illustrating the improvements operatively embodied in a loom;

Figure 2 is a perspective view of the improved connection, and

Figure 3 is a perspective view of the parts of said connection in detached relation.

Like reference characters designate like 45 or similar parts in the different views.

In the drawings a loom is partially shown of which the operating rod for the let-off mechanism is shown at A to be driven as is common practice from a rock shaft at B. Supplanting the usual lugs and cotter pin connections that cause undue wear and is liable to separate through breakage of the cotter pins, is the following construction.

55 A connecting arm is provided at 10 which

is adapted to be connected to a crank arm 11 which extends rigidly from the shaft B or a part rigidly attached thereto. A bolt 12 may connect the arms 10 and 11, passing through suitable openings therein, the one in the arm 10 being designated 13 and preferably enlarged so that the arm 10 may be secured at different adjustments relatively to the arm 11. In addition, arm 10 may have one or more ribs at 14 to overlap the 60 sides of the arm 11, reinforce its connection therewith and prevent pivotal movement of arm 10 from the bolt 12.

Extending laterally from the arm 10 and preferably integral therewith, is a T-shaped connecting head 14. The shank of this head is designated 15 and its lateral lugs or head proper are designated 16.

The rod A is enlarged at one end as at 17 and therethrough is provided with a slot 70 of L-shape at 18 which accordingly provides an enlargement for said slot at 19 and thickens and reinforces the end 17 as at a portion 20.

The arm 10 has the head 14 first passed 80 through the enlargement 19 of the slot 18 so that its shank 15 will enter the narrower portion of the slot 18 and the lugs 16 will overlap the end 17 on one side and the arm 10 proper will overlap said end on the other 85 side. The wear is greatest at the portion 20 and accordingly the thickening of said portion in combination with the slot 19 compensates for the wear and strain incidental to actual use. In addition, the lugs 16 are 90 substantial and will not readily wear away, or become loosened or broken as is the case with cotter pins and their equivalent.

In order to facilitate the movement of the rod A on the shank 15 as a fulcrum, the latter may be rounded off or curved as at 21.

As merely one practical embodiment has been illustrated and described, it is to be understood that changes in the details may be resorted to provided they fall within the 100 spirit and scope of the invention.

I claim as my invention:—

1. In combination with a let-off rod having a slot therethrough, an arm to drive said rod having a head provided with a shank 105 and with a lug, said slot being of a size to permit passage of the lug therethrough in one position to facilitate attachment and detachment, said lug adapted to normally prevent detachment of the rod and arm, and 110

said rod and said slot having a thickened portion to accomodate wear imposed by operation of the shank.

2. In combination with a let-off rod having a slot of L-shape therethrough, an arm to drive said rod having a head T-shaped and thus provided with a shank and a lug, said slot at the larger portion adapted to permit passage of the lug therethrough to facilitate attachment and detachment, said lug adapted to normally prevent detachment

of the rod and arm, and said rod due to the shape of and at said slot having a portion to accommodate wear imposed by operation of the shank.

In testimony whereof I affix my signature in presence of two witnesses.

JOHN W. GILES.
